UNITED STATES PATENT OFFICE.

EDWARD E. CLEMENT, OF WASHINGTON, DISTRICT OF COLUMBIA, ASSIGNOR TO THE CLEMENT INTERNATIONAL ENGINEERING CORPORATION, OF CAMDEN, NEW JERSEY, A CORPORATION OF NEW JERSEY.

AUTOMATIC SWITCH FOR TELEPHONE-EXCHANGE SYSTEMS.

1,076,020.

Specification of Letters Patent.

Patented Oct. 21, 1913.

Application filed May 17, 1910. Serial No. 561,804.

To all whom it may concern:

Be it known that I, EDWARD E. CLEMENT, a citizen of the United States, residing at Washington, in the District of Columbia, have invented certain new and useful Improvements in Automatic Switches for Telephone-Exchange Systems, of which the following is a specification, reference being had therein to the accompanying drawing.

10 My invention relates to so-called automatic switches for telephone systems, that is to say switches employed to effect connection between different lines or circuits, by mechanical means electrically controlled.

15 It has particular reference to such switches as are used in telephone systems for selectively connecting a given circuit with any one of a number of other circuits. The switches heretofore employed for this purpose are well exemplified in Patents Nos. 815,176 and 815,321, granted to Keith and Erickson March 13, 1906.

20 The object of my invention is to produce a switch which shall be at once simpler and more efficient than those heretofore available, quickness and certainty of movement being points particularly in mind.

25 In order to attain my object I provide one or more banks containing the contacts from which selection is to be effected, mount the same upon a suitable support, and associate therewith a frame carrying a spindle and wipers, together with operating magnets therefor. In order to secure quickness and 30 certainty of operation I mount the magnet armatures upon knife-edges, and construct their moving parts of one of the lighter metals such as aluminum.

35 The invention which I shall describe and claim herein is in the nature of an improvement on that disclosed in my prior application, filed November 13, 1907, Serial No. 402,027.

40 My invention is illustrated in the accompanying drawings wherein:

45 Figure 1 is a side view of my improved switch; Fig. 2 is a rear view thereof; Fig. 3 is a plan view of the same; Fig. 4 is a plan view of one electromagnet unit removed 50 from the frame; Fig. 5 is an end view thereof looking in the direction of the arrow in Fig. 4, and showing a latch for the release movement, this particular unit being the rotary magnet; Figs. 6 and 7 are detail fig-

ures of the spindle and its ratchets removed 55 from the frame; Fig. 8 and Fig. 9 are plan and face views of a portion of a contact bank, showing the method of inserting and securing the springs therein.

55 Referring to the drawings, 1 represents 60 a plate upon which the different parts of the switch are mounted. Upon the back of this plate are secured the banks 3 and 4, and upon the front of it a frame 2 carrying the spindle 5 with its wipers, the 65 operating magnets 3 and 7, and the release magnet 8. The banks 3 and 4 are alike in their construction and a brief description of one will suffice for both. The bank 3, therefore, consists of ten straight vertical rows 70 of ten pairs of contacts each, held in a body of insulating material, and clamped between side plates 3^a and 3^b, each of which is provided with ears 3^c, through which screws 3^d are inserted to secure it upon the plate 1. The body 75 of insulation 3^e is preferably built up of layers or curved strips of a suitable insulating composition, but it may be molded solid, the contacts in that case being set in the die and the composition molded around 80 them. Where the strips are employed, they are slotted or grooved to receive the contacts, which are placed therein as indicated in Figs. 8 and 9, and then the successive strips are piled up to form the bank. 85 Where the slots are made exactly the same width as the contacts, however, there is a tendency for the latter to work loose, and I remedy this by having the strips molded with the slots from .003 to .008 of an inch 90 shallower than the width of the springs. The contacts being insulated and the strips piled up, the top and bottom plates 3^a and 3^b are put in position, the screws 3^d are inserted, passing from the top to the bottom 95 plate and tapped into the latter, the bank is placed in an oven and heated sufficiently to soften the composition a little, and then by tightening the screws or otherwise forcing the plates 3^a and 3^b together, the contacts will be forced into the substance of each strip, both above and below, until the surfaces of the strips meet, thus insuring an absolutely tight grip. In Fig. 8 I have shown each contact 3^e with a small return 100 bend in it at 3^b, but with a straight tail on the outside of the bank. The bend 3^b is for the purpose of preventing longitudinal dis-

placement outwardly and to prevent the same inwardly, I may adopt either of two expedients, that is to say the one shown in Fig. 8, on the left hand side, where the contact is given a quarter turn outside the bank, the other where it is given a straight offset or bend on the outside, as shown in Fig. 9. These two methods may be combined if desired, and it will be observed in Fig. 9 that the offset at 3^h affords an opportunity to increase the insulation between the respective contacts by setting the offset in opposite directions in alternate rows and by setting it oppositely for each pair if desired.

15 The contacts are all placed with their surfaces vertical and the wipers are slipped around beneath the rows of contacts until the desired row is reached, and then pass up that row. This it will be observed is a reversal of the method employed in the Keith and Erickson switches hereinbefore referred to. In those and in all of the Strowger switches the movement is up to the row and then 20 around the row, the contacts being arranged with their flat surfaces horizontal. The vertical arrangement, however, I consider to be better, because it makes the contacts self-cleaning, which is an important point in 25 apparatus of this character.

30 The frame 2 consists of a finished white metal or similar casting having a vertical straight-faced member or body 2^a, with upper and lower attaching arms 2^b and 2^c respectively. Carried upon suitable forward extensions 2^g, 2^h and 2^k, are front mounting plates 2^e, 2^f and 2^m. These are of course connected by suitable webs or flanges in casting so that the whole frame is properly 35 braced without superfluous metal. The arms 2^b have an intermediate horizontal web 2^c carrying the upper bearing for the spindle 5, and an extension 2^d of this web carries the vertical and rotary cutoff contact springs 9 and 10 which are actuated by 40 the spindle as it returns to its zero or normal position. A similar web at the bottom of the frame carries the lower bearing for the spindle, these bearings being formed in separate collars or bushings inserted through 45 openings molded in the webs of the frame.

50 The spindle 5 slides vertically and also rotates in the bearings 5^a and 5^b. This vertical or sliding movement is produced by 55 means of a rack 5^c, best shown in Figs. 1, 6 and 7. This rack does not turn with the spindle, but has upper and lower collars 5^c and 5^{c₂} through which the spindle passes and through which it turns, these collars lying between 60 fixed collars or sleeves 5^d and 5^e secured upon the spindle in any suitable way as by means of the pins 5^f. The upper collar 5^d carries the rotary ratchet 5^g, and the lower collar 5^e carries the casing 5^h within which 65 the coiled spring is carried for restoring the

switch to its zero position. This coiled spring is secured at its inner end upon the spindle and its outer end to the casing 5^h as indicated at 5ⁱ in Fig. 1. The casing carries the pin 5^j which slides along the edge of the frame 2^a and thereby keeps the tension of the spring constant for all vertical positions.

70 The retaining pawl for the vertical ratchet, and the teeth which coöperate with it are on the side thereof as shown at 5^{e₂} in Figs. 6 and 7, and are of the ordinary conformation.

75 As a means for preventing rotation of the spindle after it starts to reciprocate, I provide a vertical knife edge 2^q fixed on the inside of the frame member 2^a. The rotary ratchet 5^g leaves the pawl 11^a as soon as the spindle commences to rise, but the first step which thus disengages it from the initial holding device 11^a brings it into engagement with the knife edge 2^q through the medium of any space between the teeth which happens to be in line with the knife edge. Thus it is impossible for the spindle 80 ever to rotate after it is reciprocated. The rack 5^c is likewise prevented from rotating by means of slides or stops on the frame member 2^a and also by its engagement with the dog 11.

95 Coöperating with both the rotary and vertical ratchets is a double detent dog 11, pivoted at 12 and having an upper straight member 11^a engaging the rotary ratchet, a lower hooked pawl 11^b engaging the side 100 ratchet 5^{c₂} on the vertical rack, and two tails 11^c and 11^d, the former engaged by the end of the armature lever 8^a of the release magnet 8, and the latter adapted to engage and to be held by a latch 6^a pivoted on the 105 frame 6^b of the rotary magnet 6 (see Fig. 5). In operation, when the release magnet is energized, the lever 8^a is thrown over (to the right in Fig. 2), the tail 11^d of the dog 11 is thrown with it and engages the latch 110 6^a, being held thereby so that in case the release magnet is deenergized before the release switch is fully restored, the dog will not be released, and the complete restoration of the switch will not be interfered with. 115

The latch 6^a is a bell crank pivoted at its angle and normally held in latching position by a spring 6^c bearing upon its tail 6^d. The armature lever 6^e of the rotary magnet is the first to move when the switch is actuated, and its first movement, lifting the tail of the latch, releases the dog 11, and permits the pawls 11^a and 11^b to engage their respective ratchets and thereby properly perform every function of holding the spindle in a position to which it may be stopped and until it is again released.

120 The three magnets 6, 7 and 8 are shown as identical and interchangeable units, but this feature in itself forms no part of my 130

present invention. It is shown merely as a matter of convenience and because in its finished form the switch has been made in that way, from parts designed in the shop to be interchangeable. As shown, the only difference between the rotary and vertical units and the release unit lies in the provision of differently shaped pawls and in the case of the release unit the absence of a pawl, the bifurcated end of its lever 8^a striking directly against the inclined tail 11^c of the detent dog. In Fig. 4 I have shown one unit detached, its armature lever being fitted with a pawl. A description of this unit will suffice for all the units, and as Fig. 4 is a plan view only, reference may be had to any of the units in the other figures to supplement this illustration. For the purposes of this description we will assume that Fig. 4 represents the rotary unit 3. This is mounted on a frame plate 6^b, which may be of iron or other suitable metal. The two magnet cores 6^c are secured to the plate by screws 6^d (see Fig. 5), and are provided with an iron yoke 6^e, if the frame plate is of non-magnetic metal. Along one side of the electromagnets lies an extension member of the frame, 6^f, constituting a support for the armature. This armature is formed of a plate of soft iron 6^g, with an aluminum bell crank lever 6^h riveted to it. A long arm 6^m of this lever constitutes the continuation of a rib formed up in the aluminum body, and as the lever is beveled off at its end, a bifurcation results, as indicated at 6ⁿ, the two sides of the lever forming cheek pieces for the reception of the pawl 6^p normally held with its point out by the spring 6^q, extending from the tail of the pawl at 6^r to a fixed stud 6^s. Where the unit is to be used for release, as indicated at 8 in Fig. 1, the pawl, spring, and stud are omitted.

Another feature which in itself forms no part of the present invention but which will be described herein for the sake of completeness, is that of the adjusting means for the working knife edges, and for the armature levers. The armature plate 6^g is scored across near the top, so as to take over the knife edge 6^t, formed on a tapered plate 60, secured upon the top of the frame bar 6ⁱ by screws extending through washers and slots in the taper plate. The inclined edge of this plate rests against a shoulder 61 formed on the frame plate, and adjustment of the armature to and from the cores is readily accomplished by loosening the screws and sliding the plate laterally, this motion being permitted by the slots, and the plate 60 resting against the shoulder 61 in all positions, so that all strain and wear is taken up by the frame plate. The arrangement of this shoulder and the strip are well shown in Fig. 1, where the magnet 7 is presented in side elevation. It should be noted that

Fig. 5 shows the unit turned upon its side, with the top to the left, as indicated by the arrow in that figure.

The armature, and the bell crank lever 6^h are held against the top of the frame plate 6^b, by means of helical tension springs 6^u, hooked at one end into eyes 6^v attached to a transverse plate 6^w carried on the frame plate, and formed with an opening through which the lever arm 6^m passes. A transverse 75 sliding plate similar in its movement to that carrying the knife edge 6^t is provided under this plate 6^w, to adjust the throw up and down of the lever, as indicated at 6^x in Figs. 2 and 4, and at 7^x in Fig. 1. The throw of the pawls 6^p and 7^p of the rotary and vertical magnets respectively is limited by fitting slides to the frame member 2^a, as indicated in Figs. 1 and 2.

It is particularly important that the motion of the actuating pawls be positively limited, in order to avoid any overthrow, and to positively withdraw each pawl from its ratchet when its armature retracts, so that it may fall into the succeeding tooth. 85 This may be attained by fixed stops, but in Fig. 2 is shown an adjustable limiting plate or slide for the vertical pawl, which is marked 6^x in that figure and 7^x in Fig. 1. By loosening the holding screws, and sliding 90 the plate slightly from side to side, the edges of the opening y in the plate may be raised or lowered as required. In operation, when the pawl is thrown up by the action of the magnet, its nose is forced into one of the 95 indentations in the vertical ratchet, so that it carries the spindle with it. As the upper edge of the pawl comes against the upper end of the opening y in the limiting plate, its own motion stops, and because of the 100 peculiar shape of the nose and of the indentations, the vertical motion of the spindle also ceases instantly, thus obviating any possible liability to "overthrowing", or moving more than the single step intended. As the 105 pawl drops, its lower edge strikes the lower edge of the opening y, and it slides out, tensioning its spring 6^q, ready to engage the next tooth if the magnet is again energized.

In assembling this switch, the frame 2 is 110 secured to the plate 1 through the medium of short posts 12^a, by screws passing through the ends of the arms 2^b and 2^c. The length of these posts is such that when the screws are set up, the spindle 5 is centered with 115 regard to the curvature of the banks, so that its wipers 5^w and 5^x (see Figs. 1 and 3) will engage the contacts in the banks when the spindle is rotated by the magnet 6 and raised by the magnet 7. In operation the 120 magnet 6 works first, turning the spindle until the wipers w and x come under the desired row of contacts, the spindle being held in position by the nose 11^c on the dog 11, engaging the rotary ratchet 5^s. The 130

spindle and its wipers are then raised step by step through the agency of the magnet 7, until the wipers rest upon the desired contacts in the row selected. The switch is 5 adapted to be used for any purpose, and in any circuit, either as a selector or connector. To restore it to zero, the magnet 8 is energized, attracting its armature and causing the end of its lever 8^a to force over the tail 10 11^c of the dog 11 until the tail 11^d engages and is held by the latch 6^a on the rotary mounting plate. The detents 11^a and 11^b are then disengaged from the respective ratchets 5^g and 5^e, and the spindle drops of 15 its own weight until the wipers have cleared the row with which they were engaged, after which the spring in casing 5^h turns the spindle back to the zero position in the drawings.

For convenience in making connections, a 20 set of jacks are provided on the lower portion of the plate 1, as indicated at 15, co-operating blades 16 being carried on the lower part of the frame 2. The jack springs 15 are mounted in an insulating strip and 25 extend through to the back of the plate for ready access in wiring, and the upper ends of the blades 16 are notched for connection to the terminal wires of the magnets and the wipers.

30 I am aware that some changes may be made in matters of detail in this structure, without affecting the design or the essential features of my invention. I wish it thoroughly understood that all such non-essential changes or modifications are contemplated by me, if within the scope of the appended claims.

Having thus described my invention what I claim and desire to secure by Letters Patent is—

1. In an electric switch, bank contacts, wiper contacts, a spindle carrying the wipers, means for rotating the spindle, and a non-rotating rack lying parallel to and carrying journal bearings on its ends for the spindle and adapted when moved to reciprocate the same.

2. In an electric switch, a frame, bank contacts carried on said frame and arranged in a plurality of rows, wiper contacts co-operating with the bank contacts, a spindle carrying said wipers and journaled for rotation in the frame with an electromagnet adapted to rotate the same, a rack lying parallel to and carrying journal bearings on its ends for the spindle, an electromagnet for reciprocating the rack, and means for preventing rotation of the rack, whereby rotation and reciprocation of the spindle may be 55 accomplished, and the wipers adjusted to any desired bank contact in any row.

3. In an electric switch, a frame, bank contacts carried on said frame and arranged in a plurality of rows, wiper contacts co-operating with the bank contacts, a spindle

carrying said wipers and journaled for rotation in the frame with an electromagnet adapted to rotate the same, a rack lying parallel to and carrying journal bearings on its ends for the spindle, an electromagnet for reciprocating the rack, means on the frame for preventing rotation of the rack, and a detent co-operating with the rack to maintain the switch in position after its wipers have been set, together with a release magnet for disengaging said detent from the rack and 75 restoring the parts to normal.

4. In an electric switch, a frame, bank contacts carried on said frame and arranged in a plurality of rows, wiper contacts co-operating with the bank contacts, a spindle carrying said wipers and journaled for rotation in the frame with an electromagnet adapted to rotate the same, a rack carrying journal bearings on the spindle and an electromagnet for reciprocating the rack, means on the frame to prevent rotation of the rack, a detent adapted to hold the spindle against reverse rotation, another detent adapted to engage teeth on the rack, and a release magnet adapted when energized to disengage said detents and restore the parts to normal condition.

5. In an electric switch, a frame, bank contacts carried on said frame and arranged in a plurality of rows, wiper contacts co-operating with the bank contacts, a spindle carrying said wipers and journaled for rotation in the frame with an electromagnet adapted to rotate the same, a rack carrying journal bearings on the spindle and an electromagnet for reciprocating the rack, means on the frame to prevent rotation of the rack, a detent adapted to hold the spindle against reverse rotation, another detent adapted to engage teeth on the rack, means on the frame to prevent reverse rotation of the spindle after reciprocation and a release magnet adapted to act upon said detents so as to first produce reverse reciprocation of the spindle from any position in which it has been set, whereby it may be disengaged from the frame detent, and then permitting reverse rotation of the spindle, to bring the wipers into zero or normal position.

6. In an electric switch, the combination with the following instrumentalities: a frame, bank contacts and a spindle carrying wipers, an actuating magnet structure comprising a supplemental frame, a magnet core, an extended armature and retracting springs, all secured together and to the switch frame as a detachable interchangeable unit, a release magnet structure similar to the actuating magnet structure and secured in the same manner to the switch frame, means for actuating the spindle controlled by the actuating magnet, a holding dog or detent for the spindle adapted to maintain it in fixed position when actuated,

- and a latch for said dog or detent comprising a lever pivoted at an intermediate point to the supplemental frame of the actuating magnet structure with one arm extending 5 into position to be engaged by the armature lever of the actuating magnet, and with another arm extending from the pivot into proximity with the holding dog, and provided with a terminal catch for said dog.
- 10 7. In an electric switch, the combination of the following instrumentalities, bank contacts, a spindle carrying coöperating wipers, a frame carrying the spindle, a unitary electromagnet structure detachably 15 secured to the frame and comprising an electromagnet, its armature, and an actuated spindle engaging device, a detent adapted to hold the spindle in actuated position, a release magnet adapted to retract 20 the said detent and release the spindle, and a latch to retain said spindle in retracted position, said latch being mounted on and forming a part of said detachable structure of the electromagnet and operable by said 25 electromagnet to release said detent.
8. In an electric switch, the combination of the following instrumentalities, bank contacts, a spindle carrying coöperating wipers, a detachable electromagnet having 30 an armature and armature lever carrying means to actuate the spindle, a detent for holding the spindle in actuated position, a second electromagnet having an armature and armature lever carrying means to trip 35 said detent so as to release the spindle and permit its restoration to normal, and a spring latch pivoted on the actuating electromagnet structure, said latch having one member adapted to engage and hold the 40 detent when tripped, and another member rising in the path of the armature lever of the actuating magnet, whereby the momentary energization of the second or release electromagnet will trip and latch the detent
- so as to insure complete restoration of the 45 spindle, and the first movement of the actuating magnet lever will unlatch the detent, and permit it to again engage the spindle.
9. In an electric switch, a frame, bank contacts and a spindle carrying wipers, a rotary ratchet for said spindle, an actuating pawl for said ratchet and an actuating magnet for the pawl, means for moving the spindle longitudinally, and an extended detent or knife edge fixed rigidly on the frame 50 parallel to the spindle, adapted to engage said rotary ratchet after rotation and upon subsequent longitudinal movement of the spindle, whereby rotation of the latter in either direction during said longitudinal 55 movement is prevented.
10. An electric switch comprising bank contacts, a spindle mounted in a suitably positioned frame and carrying wipers coöperating with said contacts, an actuating electromagnet adapted to operate said spindle to carry its wipers into engagement with said contacts, said electromagnet being mounted in a plane passing to one side of said spindle, but substantially parallel thereto, a detent for holding said spindle in actuated position, having its main body in a plane including said spindle, electromagnetic means for retracting said detent, and a latch associated with said first named actuating electromagnet and adapted to retain said detent in retracted position, together with actuating connections between said latch and said electromagnet whereby the latch is operated upon actuation of the magnet to release said detent. 70 75 80

In testimony whereof I affix my signature in presence of two witnesses.

EDWARD E. CLEMENT.
